RECEPTACLE HANDLING DEVICE

Raymond W. Wilson, Ferndale, Mich., assignor, by mesne assignments, to Ford Motor Company, Dearborn, Mich., a corporation of Delaware

Application June 10, 1953, Serial No. 360,641

4 Claims. (Cl. 214—313)

The present invention relates to a material handling apparatus and, more particularly, to a device for the handling and dumping of receptacles containing flowable material.

In an earlier filed application of Walter W. Sewell and myself, Serial No. 310,228, filed September 18, 1952, and assigned to the assignee of the present invention, there is disclosed a generally similar receptacle handling apparatus. Such apparatus includes a tractor-mounted loader or similar device having a vertically movable, load-supporting boom. The receptacle handling mechanism is attached to the boom and includes a receptacle-engaging arm pivotally connected to a support structure for relative movement upon actuation of a power means, such as a hydraulically actuated cylinder.

The present invention is particularly concerned with the provision of an improved receptacle carrying and dumping structure and with an improved latch assembly actuatable during dumping of a receptacle to prevent displacement of the receptacle from the carrying and dumping mechanism.

It is, therefore, an important object of the present invention to provide an improved receptacle handling and dumping mechanism of the type attachable to a vertically movable boom.

Another important object is provision of a handling apparatus having a receptacle-engaging dumping arm and a support arm which are relatively movable to dump a receptacle upon actuation of a power source interposed between and protected by the elevating and dumping structure.

It is a further object to provide an improved receptacle handling device having a power-actuated dumping mechanism for at least partially inverting a receptacle and provided with a latch mechanism operable to prevent displacement of the receptacle during dumping.

Yet another object of the present invention is the provision of a receptacle dumping device having generally vertically aligned supporting and dumping arms and power-energized means for effecting relative movement of the arms to dump the receptacle and also having automatically operable means energized upon arm movement to prevent displacement of the receptacle.

The specific nature of this invention, as well as other objects and advantages thereof, will become apparent to those skilled in the art from the following detailed description, taken in conjunction with the attached sheets of drawings on which, by way of preferred example only, is illustrated one embodiment of this invention.

On the drawings:

Figure 1 is an elevational view of a material handling apparatus of the present invention;

Figure 2 is an enlarged, broken, fragmentary plan view of the apparatus of Figure 1;

Figure 3 is a sectional view, with parts shown in elevation, taken along the plane 3—3 of Figure 2;

2

Figure 4 is an enlarged sectional view, with parts shown in elevation, taken along the plane 4—4 of Figure 2;

Figure 5 is an enlarged sectional view taken along the plane 5—5 of Figure 3;

Figure 6 is a fragmentary side elevational view similar to Figure 1 particularly illustrating the receptacle dumping mechanism;

Figure 7 is a view similar to Figure 6 showing the dumping mechanism in an adjusted position;

Figure 8 is a view similar to Figure 7 showing the dumping mechanism in another adjusted position; and

Figure 9 is an enlarged fragmentary sectional view illustrating in greater detail the receptacle latching mechanism when the dumping mechanism is in the position of Figure 8.

As shown on the drawings:

In Figure 1, reference numeral 10 refers generally to a tractor or similar prime mover upon which is disposed a material handling apparatus of the present invention indicated generally by reference numeral 11.

More particularly, the device 11 includes a main structural frame 12 fixedly mounted upon the tractor 10 and including a pair of laterally spaced support plates 13 fixedly mounted upon the tractor rear axle to carry a forwardly and upwardly inclined support post 14 joined intermediate the tractor wheel base to a forwardly and downwardly extended brace 15 which is connectable at its lower forward end to the tractor frame. The members 14 and 15 define a laterally extending pivot axis 16 at their point of juncture, and a vertically swingable boom 17 is pivoted on the axis 16. The boom 17 is raised and lowered by a main hydraulic lifting cylinder 18 pivoted to the rear axle bracket 13 and powered by hydraulic fluid under pressure generated by the prime mover 10 and controlled through a valve 19 mounted on the frame 12. The boom 17 carries at its front end a laterally spaced pair of generally vertical support plates 20, best illustrated in Figure 4. It will be appreciated that a pair of booms 17 are provided and that laterally spaced pairs of plates 20 are secured to the free front ends of the booms, as by pivot pins 21.

The free upper ends of the inner plates 20 are connected to the upper ends of adjacent plates 20a by pivot pins 22 which pivotally mount to the plates 20 and 20a an elongated stabilizer rod 23. The rear ends of the stabilizer rods 23 are connected to upstanding brackets 24 mounted at the loader frame 12 in alignment with the axes 16. The upstanding brackets 24 are reinforced by a fixed, downwardly and rearwardly extending brace element 25 fixed to the rear axle bracket 13. The distance between the pivot pins 21 and 22 is substantially the same as the distance between the boom axes 16 and the pivot pins 26 joining the stabilizer bars 23 to the brackets 24. Also, the stabilizer bars 23 are of substantially the same length as the booms 17. Thus, it will be appreciated that a parallelogram is formed between booms 17, the plates 20 and 20a, the stabilizer rods 23, and the brackets 24, so that a parallel lifting action is obtained and the plates 20 and 20a always lie in a vertical plane which is substantially normal to the ground level.

The plates 20 and 20a are joined by a laterally extending, tubular main frame element 28 which also serves to laterally rigidify the booms 17. Additionally, the plates are joined by a lower tubular element 29 which has rigidly secured thereto a forwardly extending lift arm 30. As best illustrated in Figures 3 and 4, the lift arms 30 are preferably formed of channel stock having upstanding side walls 30a and a lower bottom wall 30b. The lift arms are additionally braced by downwardly and forwardly ex-

tending reinforcing plates 31 rigidly secured to the tubular structural element 28. It will be appreciated that during elevation and lowering of the boom, the lift arms 30 will be raised and lowered in a manner to assume a plurality of substantially parallel positions because of the parallelogram linkage heretofore described.

The lift arms 30 have medially mounted thereon upstanding side plates 32 secured to each of the side walls 30 of each of the arms. These plates 32 are rigid with the arms 30 and serve to provide a carrying means for an upper pivot bearing 33 journaling a hydraulically actuated cylinder 34 associated with each lift arm, as will be hereinafter more fully described.

Adjacent the extreme forward end of each of the lift arms 30, there is provided a laterally extended pivot pin 35 carrying a pair of generally triangular pivot plates 36, one such plate being mounted immediately inwardly from each side wall 30a. A cylindrical bushing 37 extends between the pivot plates 36 to maintain the lateral spacing thereof and to reinforce the bearing pin. The rear apexes of each of the plates 36 carries a mounting pin 38 secured to the clevis 39 of the actuating rod 40 of the associated hydraulic cylinder 34.

The plates 36, as best seen in Figure 5, are rigidly secured, as by welding, to the downturned side walls 42a of a dumping arm indicated generally at 42 and formed of channel stock substantially the same width as the stock forming the lift arm 30. The web portion of the channel arms 42 forms an upper wall 42b which overlies the associated cylinder 34.

Thus, it will be seen that upon actuation of the cylinders 34, the dumping arm 42 is moved relatively to the lift arm 30 to assume any one of a plurality of relatively pivoted positions, as illustrated in Figures 6 through 8, inclusive. The rear ends of the dumping arms 42 are joined by a laterally extending tubular structural element 43, and the rear ends of the dumping arms side walls 42a each carry upstanding stop plates indicated generally at 44. Each stop plate 44 provides a central notch 45 lying immediately rearwardly of an upwardly enlarged guide portion 46 and forwardly of a concave rear surface 47 which terminates in a downwardly facing stop surface 48 for a purpose to be hereinafter more fully described.

Adjacent the forward ends of the dump arms 42, there is provided a notch 49 formed in the upper or cover wall 42b and in the side walls 42a. The pivot plates 36 are similarly notched, as at 36a, to provide a laterally extended recess.

The lift arms 30 and the dumping arms 42 are adapted to elevate and dump the receptacle best illustrated in Figures 1, 2 and 6-8. This receptacle is indicated generally at 50 and preferably takes the form of an inverted square frustum-pyramid. More particularly, the box is substantially square in cross-section and comprises sheet metal side and end walls 51 which are spot welded to one another and to a metal bottom wall 52 to enclose an interior space. The box side and end walls taper downwardly and inwardly, and the upper ends of the walls partially lap tubular reinforcing elements 53 which project outwardly beyond the associated ends to form laterally and longitudinally extending trunnions 54 projecting beyond each of the four corners of the box. Since the receptacle box is square and the trunnions 54 project beyond each of the corners thereof, it will be appreciated that the receptacle may be picked up from any direction so long as one pair of side or end walls are substantially parallel to the lifting and dumping arms as shown in Figure 2. Further, the upper extremities of the side and end walls at least partially lap the trunnion elements 53 intermediate the receptacle corners and the lapping wall portions are secured, as by spot welding, to the trunnion elements. Thus, the receptacle is suspended from the tubular elements 53.

The receptacle is more fully described and claimed in the copending application of W. A. Schaich, Serial No.

3,60,667, filed June 10, 1953 and now abandoned, and assigned to the assignee of the present invention.

From Figures 2 and 3, it will be seen that the longitudinal distance between the notches 45 at the rear ends of the dump arms 42 and the notches 49 at the forward end thereof is substantially equal to the length of one side of the square receptacle 50 and that the trunnions 54 of the receptacle are received by the notches 45 and 49 when the lift arms 30 and the dumping arms 42 are inserted beneath the trunnions and the boom is elevated. Upon subsequent actuation of the cylinders 34, the dump arms 42 and the receptacle 50 carried thereby will be elevated about the pivot pin 35 joining the dumping arms to the lift arms.

It will be appreciated that it is necessary to retain the receptacle trunnions 54 in the notches 45 and 49 when the receptacle is in the fully dumped position of Figure 8. To retain the receptacle the latch mechanism best illustrated in Figures 3, 5 and 9 is utilized. This latch mechanism includes a latch link 56 pivoted at one end, as about pivot pin 57, to the side walls 30a of the lift arms and pivotally connected at its free end, as through pin 58, to a depending ear 59 formed on the latch arm 60 which is medially pivoted at 61 to the dump arm pivot plates 36. The free forward ends of the latch arm terminate in the rearwardly and upwardly directed latch extension or finger 62 which is adapted to overlie the forward receptacle trunnion 54 when the receptacle is in its dumping position. The operation of the latching mechanism will be appreciated since the pivot movement of the latch lever 56 about its pin 57 is eccentric with respect to the axes of dumping movement of the dump arms 42 and the increase in the distance between the pivot pins 57 and 61 during dumping movement will cause the latching finger 62 to overlie the trunnion 54.

When the receptacle is in its dumping position, it will be noted that the rear lateral trunnions 54 will abut the horizontal stop surface 48 overlying the notch 45 and both of the trunnions are retained to prevent displacement of the receptacle.

Thus, it will be appreciated that the present invention provides improved receptacle handling and dumping mechanism. The dumping actuating means, i. e. the cylinders 34, are entirely enclosed within the channelled lifting and dumping arms 30 and 42, respectively, when the device is in its position of Figure 1, so that the cylinders are completely protected. Also, the positioning of the dumping axes at the extreme forward end of the lift arms elevates the receptacle during dumping movement and additional dumping height is obtained. Further, the receptacle is fully retained on the dumping arms when in its partially inverted dumping position, so that there is no possibility for displacement of the receptacle during dumping.

It will, of course, be understood that various details of construction may be varied through a wide range without departing from the principles of this invention and it is, therefore, not the purpose to limit the patent granted hereon otherwise than necessitated by the scope of the appended claims.

I claim:

1. A receptacle handling device for use with a receptacle having laterally projecting trunnions, comprising a pair of laterally spaced lift arms, means for elevating and lowering said lift arms, a dumping arm overlying each of said lift arms respectively and pivotally connected thereto for movement with said lift arms and for independent movement relative thereto; means operatively interposed between associated lift arms and dumping arms for effecting such relative movement, said dumping arms being adapted to engage the receptacle trunnions to elevate the receptacle and to partially invert the same upon relative lift arm-dumping arm movement, and a latching structure for preventing displacement of said receptacle from said dumping arms,

including an articulated linkage pivoted to said lift arms in spaced relation to the pivoted connection of said dumping arms thereto and pivoted to said dumping arms in spaced relation to the dumping arms-trunnions engagement, and a latching extension carried by said linkage to overlie one of said trunnions.

2. In a receptacle handling device for use with a receptacle having a pair of longitudinally spaced laterally extending trunnions, a pair of laterally spaced vertically movable lift arms having freely projecting forward ends, a dumping arm respectively overlying each of said lift arms, means pivotally interconnecting the forward ends of said lift arms and said dumping arms, said dumping arms having notches adjacent the forward ends thereof to receive corresponding trunnions on said receptacle and said dumping arms supportingly engaging the other trunnions of said pair, means for effecting relative pivotal movement of said dumping arms about said pivotal interconnections, a latch link pivoted to one of said lift arms in spaced relation to said pivotal interconnection, a latch arm pivoted to the free end of said latch link and to said dumping arm, and an arcuate latching finger on said latch arm adapted to overlie said notch when said dumping arm is moved to prevent displacement of said trunnions therefrom.

3. A receptacle handling device for use with a receptacle having laterally projecting trunnions, comprising a pair of laterally spaced lift arms, means for elevating and lowering said lift arms, a dumping arm overlying each of said lift arms respectively and pivotally connected thereto for movement with said lift arms and for pivoted movement relative thereto, means operatively interposed between the associated lift arms and dumping arms for effecting such relative movement, said dumping arms being adapted to engage the receptacle trunnions to elevate the

35

receptacle and to partially invert the same upon relative lift arm-dumping arm movement, and a latching structure for preventing displacement of said receptacle trunnions from said dumping arms, including a pair of articulated links pivoted to said lift arms and to said dumping arms, respectively, for relative movement upon elevation of said dumping arms, and a latching extension carried by said linkage to overlie one of said trunnions upon such relative movement.

4. In a receptacle handling device for use with a receptacle having opposing laterally extending trunnions, a pair of laterally spaced vertically movable lift arms having freely projecting forward ends, a dumping arm respectively overlying said lift arms, means pivotally interconnecting the forward ends of said lift arms and said dumping arms, said dumping arms having notches adjacent the forward ends thereof to receive corresponding trunnions on said receptacle, means for effecting relative pivotal movement of said dumping arms about said pivotal interconnections, a latch link having one end pivoted to one of said lift arms in spaced relation to said pivotal interconnection, a latch arm having one end pivoted to the free end of said latch link and medially pivoted to said dumping arm, and an arcuate latching finger on the other end of said latch arm adapted to overlie said notch when said dumping arm is moved to prevent displacement of said trunnions therefrom.
